CLAIM

The ornamental design for a sunshade for plants, substantially as shown and described.

DESCRIPTION

FIG. 1 is a perspective view of a sunshade for plants showing my new design;

FIG. 2 is a side elevational view thereof;

FIG. 3 is a top plan view thereof; and

FIG. 4 is a bottom plan view thereof.

The cross line shading is understood to continue across the surface of the sunshade and to represent conventional fabric.
